UNITED STATES PATENT OFFICE.

CHARLES A. HAMMEL, OF LOS ANGELES, CALIFORNIA.

HYDROCARBON-BURNER.

1,238,513.

Specification of Letters Patent. Patented Aug. 28, 1917.

Application filed October 9, 1916. Serial No. 124,634.

To all whom it may concern:

Be it known that I, CHARLES A. HAMMEL, a citizen of the United States of America, residing at Los Angeles, in the county of Los Angeles, State of California, have invented new and useful Improvements in Hydrocarbon-Burners, of which the following is a specification.

This invention relates to that class of hydrocarbon burners in which oil is moved through a burner head by means of steam or air under pressure and commingled therewith, and pertains especially to improvements in my invention hydrocarbon burners disclosed in United States Letters Patent 748,862, January 5th, 1904.

The objects of my invention are to improve the construction, whereby the burner may be quickly reassembled, after having been taken apart for any purpose; and to provide a construction whereby the durability of the burner is increased.

I have found that in reassembling burners of the type disclosed in the Letters Patent above referred to, the mechanics often fail to exactly aline the several parts, thereby causing incorrect distribution of the oil in the mixing chamber, with a consequent unbalancing of the flame. Due to the small dimensions of some of the steam passages leading from the equalizing chamber to the mixing chamber, slight displacement will cause unbalancing. To the end that correct alinement in assembling may be secured, I have provided means for insuring correct position of the parts with respect to each other.

I have also provided means for straining the steam to prevent impurities from passing through the head and also means for preventing passage of condensed steam through the head. The top and bottom walls of the mixing chamber wear due to the passage of steam, water and oil therethrough. In the invention disclosed by my Letters Patent above referred to, I provide for the renewal of the top and bottom walls by using removable plates. In the present invention, I have decreased this wear by straining the steam and separating therefrom foreign matter and the water of condensation.

I accomplish these objects by means of the embodiment of my invention, illustrated in the accompanying drawings, in which:

Figure 1 is a perspective view of the burner head.

Fig. 2 is a central, vertical longitudinal section of the burner head.

Fig. 3 is a view looking upwardly of the upper part of the head. 60

Fig. 4 is a plan view of the base of the head.

Fig. 5 is a front view of the upper rear portion of the head.

Referring more particularly to the drawing, the burner head is comprised of a base 6, upon which is mounted a rear part 7 and a tip part 8.

Base 6 is provided with a longitudinally extending steam inlet bore 9 threaded at 70 the end for receiving a steam pipe. A port 10 communicates with said bore and opens through the top of said base. The forward end of the bore is reduced in diameter and a condensation port 11 communicates with the 75 upper part of the base at the forward end. A recess is formed in the top face of the base for the reception of a wear plate 12. Below the wear plate a recess 13 is countersunk. the latter flaring laterally from the condensa- 80 tion port 11 and being of relatively small depth.

The upper rear part 7 of the head has an equalizing chamber 14 formed in the lower face. The chamber is formed with an inclined wall 16' at the forward end, thereby forming extensions 15' and 17'. Leading from the equalizing chamber are three ducts 15, 16, and 17. The outer ducts 15 and 17 communicate with the extensions 15' and 17', 90 converge and are high and narrow; they discharge steam on lines which will intersect each other in the mixing chamber and thereby thoroughly mix and commingle steam and oil. A cylindrical strainer 18 of perforate 95 material is placed in equalizing chamber 14 above port 10. Above the equalizing chamber and extending longitudinally of the head portion 7, is an oil supply inlet 19 suitably threaded at the end to receive an 100 oil supply pipe. An oil duct 20 of reduced diameter communicates with inlet 19 and is directed downwardly toward the lower face to a point above steam duct 16 and between ducts 15 and 17. Fixed to the head portion 105 7 is a dowel pin 21, which projects slightly from the front face and is inclined thereto.

The tip part 8 is provided with a mixing chamber 22 which flares outwardly. Its smaller dimension is equal to the distance 110 between the outer wall of ducts 15 and 17. When in position, the rear of chamber 22

should exactly register with ducts 15 and 17, so that the side walls exactly register with the steam ducts. A flaring passage is thereby formed in which the steam and oil is 5 mixed, and in which there are no projections or recesses to unbalance the distribution of steam and oil in the chamber. Such construction I have found necessary for an efficient working of the head. Channels are 10 formed at the upper portion of the equalizing chamber for the reception of wear plate 23. A recess is formed on the rear base of the tip 8 to receive the projecting dowel pin 21. To hold wear plate 23 in position, a 15 set-screw 24 is provided.

The head is assembled by mounting head part 7 upon base 6 and securing it thereto by means of bolts 25. Wear plate 12 is then placed in position, and tip 8 placed on base 6. Bolts 26 are then tightened up securing tip 8 to the base. As the bolts 26 are tightened the tip is alined with respect to the base, so that the side walls of the mixing chamber and ducts 15 and 17 exactly register. This is a very important feature of my invention. I have found that unsatisfactory and inefficient operation of the old type of burner without the dowel pin, after having been taken apart for repairing or cleaning, 25 was due to a failure of the mechanic to properly align the tip 8 and rear portion 7 in reassembling the burner. A displacement of one sixty-fourth of an inch from true alinement will materially decrease the efficiency of the burner and result in unsatisfactory operation. With my improvement, it is impossible for the burner to be reassembled without perfect alinement of the steam ducts and mixing chamber.

40 Water of condensation enters port 9 with the steam and collects in the well formed below port 10, and is forced forwardly through the condensation port 11, spread in recess 13, and discharged out at the forward 45 end of the head below the flame. Any boiler scale, dirt or foreign matter in the steam is caught by strainer 18, and is prevented from passing out through the mixing chamber. In this way the life of wear plates 12 and 23 50 is increased, and the liability of clogging decreased. These factors all materially add to the efficiency and satisfactory operation of the burner head. On disassembling the burner for cleaning and renewal, perfect alinement in reassembling is assured and therefore, efficient and satisfactory operation.

What I claim is:

60 1. A burner comprising a base having a steam inlet, a lateral portion communicating therewith, and a condensation port at the end thereof; a part having a steam equalizing chamber, steam ducts communicating therewith, and an oil duct; a strainer disposed in said equalizing chamber to catch

foreign matter entering said lateral port; a tip having a mixing chamber communicating with said steam and oil ducts; and a dowel pin disposed between said part and said tip insuring alinement of said ducts and 70 said mixing chamber.

2. A burner comprising a base having a steam inlet, a lateral port communicating therewith, and a condensation port at the end thereof; a part having a steam equalizing chamber, steam ducts communicating therewith, and an oil duct, a strainer disposed in said equalizing chamber to catch foreign matter entering said lateral port; a tip having a mixing chamber communicating with said steam and oil ducts; and means mounted on said burner for alining said ducts and mixing chamber. 75 80

3. A burner comprising a base having a steam inlet port, a lateral port communicating therewith, and a condensation port at the end thereof communicating with the outside of said base; a part having an oil duct, and a steam duct communicating with said lateral port; a tip having a mixing chamber 85 communicating with said steam and oil ducts, and a dowel pin disposed between said part and said tip for insuring alinement of said ducts and said mixing chamber. 90

4. A burner comprising a base having a steam inlet, a lateral port communicating therewith, and a condensation port at the end thereof communicating with the outside of said base; a part having an oil duct, and steam ducts communicating with said 100 lateral port; a tip having a mixing chamber communicating with said oil and steam ducts, and means mounted on said burner for alining said ducts and mixing chamber. 95

5. A burner comprising a base having a steam inlet, a lateral port communicating therewith, a condensation port at the end thereof communicating with a condensation outlet, a part having a steam equalizing chamber, steam ducts communicating therewith, and an oil duct; a strainer disposed in said equalizing chamber to catch foreign matter entering said lateral port; and a tip having a mixing chamber disposed above 105 110 said condensation outlet, said mixing chamber communicating with said oil and steam ducts. 115

6. A burner comprising a base having a steam inlet port, a lateral port communicating therewith, and a condensation port at the end thereof communicating with a condensation outlet; a part having a steam equalizing chamber, steam ducts communicating therewith, and an oil duct; a strainer disposed in 120 125 said equalizing chamber to catch foreign matter entering said lateral port; and a tip having a mixing chamber communicating with said steam and oil ducts.

7. A burner comprising a base having a steam inlet, a lateral port communicating 130

therewith; a part having a steam equalizing chamber, steam ducts communicating therewith, and an oil duct; a strainer disposed in said equalizing chamber to strain foreign 5 matter entering said lateral port; and a tip having a mixing chamber communicating with said steam and oil ducts.

8. A burner comprising a base having a steam inlet, a lateral port communicating therewith, and a condensation port at the 10 end thereof communicating with a condensation outlet; a part having an oil duct, and steam ducts communicating with said lateral port; and a tip having a mixing chamber

disposed over said condensation outlet, said 15 mixing chamber communicating with said steam and oil ducts.

9. A burner comprising a base having a steam inlet, a lateral port communicating therewith, and a condensation port at the 20 end thereof communicating with the outside of said base; a part having an oil duct, and steam ducts communicating with said lateral port; and a tip having a mixing chamber 25 communicating with said oil and steam ducts.

CHARLES A. HAMMEL.
